UNITED STATES PATENT OFFICE.

EDWIN S. BROWNE, OF RIVERTON, NEW JERSEY.

BOOK.

1,074,833.

Specification of Letters Patent.

Patented Oct. 7, 1913.

Application filed October 23, 1911. Serial No. 656,160.

To all whom it may concern:

Be it known that I, EDWIN S. BROWNE, a citizen of the United States, residing at Riverton, in the county of Burlington and State of New Jersey, have invented certain new and useful Improvements in Books; and I do hereby declare the following to be a full, clear, and exact description of the invention, such as will enable others skilled in the art to which it appertains to make and use the same.

The present invention relates to books, and more particularly to books of the loose leaf or loose unit type.

15 The object of the present invention is to produce a loose unit book which has provision whereby a plurality of sets of loose units or signatures may be independently retained in the binder cover, which is pleasing 20 in appearance and cheap to manufacture, and which is particularly suitable for a check book.

With the above object in view the present invention consists in the loose unit book 25 hereinafter described and particularly pointed out in the claims.

In the drawings, Figure 1 is a perspective view of the check book opened illustrating the manner in which the filler units may be 30 inserted; Fig. 2 is a perspective view of the binder plate detached; Fig. 3 is a sectional view taken along the line 3—3 of Fig. 2; Fig. 4 is a sectional view taken along the line 4—4 of Fig. 2, and showing in dotted 35 lines the manner in which the binder plate is secured in the cover; Fig. 5 is a view similar to Fig. 3 showing a binder-hook open and a signature placed thereon; Fig. 6 is a front view of a check record signature; Fig. 7 is a 40 front view of a check signature; Fig. 8 is a detail view showing the form of wire staple or stitch used as a fastening device for the signatures; Fig. 9 is a view of a check record signature laid flat showing the innermost 45 pages; Fig. 10 is a view of a check signature laid flat showing the innermost pages; and Fig. 11 is a perspective view 50 illustrating the manner in which the check record and check sections are assembled before being placed in the binder.

The binder comprises front and back covers 1 and 2 and a connecting back portion 3 in which is placed a binder plate 4. The inner lining 5 is laid over the binder plate 55 and over the bottoms of the binder-arch

sockets so that the only metal which is exposed is the wires which constitute the binding devices or binder-yokes. Two sets of binding devices or binder-yokes are employed and which, for convenience of designation, will be spoken of as "binder-hooks" and "binder-arches." Each binder-hook 6 is formed of a piece of spring wire and has a hook portion 7, upon which the signatures are held or strung, and an axle portion 8, by 60 means of which the binder-hook is mounted in the binder plate. The axles 8 are provided with offset portions 9 which act as the catches to hold the hooks in open and in closed positions. Each binder-arch 10 is 65 formed of a single piece of spring wire and comprises an arch portion 11 upon which the filler units are held or strung, and two substantially parallel legs 12 which extend at right angles to the plane of the arch portion and by means of which the binder-arch is snapped or secured in the binder plate. The binder plate 4 consists of a single piece 70 of sheet metal which is bent over at its sides and ends. The bent over edge along one 75 side is curled about in three places to form cylindrical tubes 20 in which the axles of the binder-hooks are journaled. The two portions of this edge between the tubes 20 are bent up at 19 and over at 21 to form chambers of substantially right-triangular cross 80 section in which the offset portions 9 of the binder-hook axles are received. When a binder-hook is opened or closed, its axle turns in the tubes 20 which are in line with 85 the lower left hand corner of the triangular chamber, as shown in Figs. 3 and 5, and the offset portion 9 slides along the overturned portion or lip 21 of the binder plate. The 90 binder-hooks are made of resilient spring 95 wire so that when the offset portion 9 is turned against the lip 21, the offset portion will be flattened somewhat to allow the axle to turn. When the binder-hook 6 is in open 100 and in closed positions, as illustrated in Figs. 5 and 3 respectively, the resilient offset portion 9 springs or bows out so that in these 105 positions it lies against those walls of the triangular chamber which are formed by the upturned part 9 of the edge and by the flat back of the binder-plate respectively and which constitutes the two legs of the right triangle of cross section of the chamber. The over and downwardly turned lip 21 along the inner surface of which the offset 110 9

slides forms the third side or hypotenuse of this right triangle.

It is obvious that the resilient offset 9 will hold the binder-hook either open or closed and that because of the flattening of the offset when moved along the lip 21 the binder hook will snap to either full open or closed position. This construction of binder-hook is very cheap to manufacture, is easily 5 snapped open and closed and is securely held in both open and closed positions. The opposite edge of the metal sheet forming the binder plate is bent up and over to form a lip 22 which lies over the down turned ends 10 of the lips 21 and makes the binder plate of uniform thickness. The lip 22 is formed with apertures 23 near its bent-up portion to receive the free ends of the binder-hooks 6 when they are closed. To form sockets 15 for the reception of the binder-arches the opposite edges of the binder plates are bent up and over to form two pairs of inwardly extending lips 24 and 25. These lips form oppositely-facing laterally-opening recesses 20 in which are held the legs 12 of the binder-arches. The edge 28 of the lip 24 is cut in a direction parallel with the axis of the binder plate. The edge of the lip 25 is cut back along the portion 29 in a direction inclined 25 to the axis of the binder plate, and is then cut sharply back at 26 at right angles to the axis of the binder plate. When the binder-arch is inserted one leg is placed in the recess under the lip 24 and the opposite leg is 30 pressed down along the inclined edge 29 until it is snapped under the lip 25. When the leg of the binder-arch is pressed against the inclined edge 29 the inclined edge wedges the leg toward the opposite leg until 35 it is parallel with the inclined edge 29, whereupon it will snap under the lip 25. Because of the sharply cut back edge 26, the inclined edge 29 is wholly beyond the leg after it is snapped beneath the lip so that the 40 inclined edge cannot act as a wedge to allow the leg to be pushed out of the recess in case the binder-arch is pulled upwardly. The stubs which are strung by staples on the binder-arches 11 are intended to be torn 45 off as fast as the checks are used so that there is no occasion to remove the binder-arches while they are fastened to the check signatures. However, if for any unexpected reason it should be necessary to remove the 50 binder-arches while they still hold some of the check signatures, a blunt pointed instrument can be inserted behind the part of the leg exposed at 27 and run along the inclined edge 29 to pry the leg from the recess under 55 the lip 25. After the stubs of the check signatures are all torn off the binder-arch 11, the binder-yokes are easily removed by being pulled endwise from their sockets. For 60 the purpose of aiding such removal, the extreme ends of the lips of the back plate are

bent over at 30 and are provided with tongues 31 which extend to the bottom of the binder-arch receiving sockets and form an inclined plane at the end of each socket over which the binder-arches are easily 70 slipped out endwise.

The tips of the plate are bent up and over the side lips at 32 to form finished ends for the binder plate. To open the binder-hooks when only the record signatures are left in 75 the binder cover, the binder cover is laid flat with all the signatures lying against the front cover. The front cover and signatures are grasped between the thumb and fingers of the left hand and the back cover 80 grasped with the right hand. By a slight pull, the signatures will lift the hooks 6 into their open position, and the signatures may be removed therefrom. Or the hook 6 may be grasped with the fingers and easily 85 opened. New signatures may then be placed on the open hooks and laid against the front cover. To close the binder-hooks, the back cover is closed, and by the pressure of the thumb against the back plate, the back plate 90 and hooks are squeezed together, the ends of the hooks snapping into the holes 23.

The check record signature 40 (or "record" signature, as it will be designated for convenience), which constitutes one of 95 the fuller units, consists of a plurality of sheets of paper folded upon themselves. The folded edge of the record signature is cut with two sets of notches 41 and 42, the notches 42 being cut somewhat deeper than 100 the notches 41. The sheets of the signature are fastened together by wire staples or stitches 43, 44 and 45. The staples 43 and 44 are inserted over the notches 41. The straight medial portion 46 of each staple extends across and closes the open mouth of the notch 41, and the ends 47 of the staple are inserted through the folded edge of the signature and clenched on its inner face, as shown in Fig. 8. The staple 45 is put 105 through the middle of the folded edge and acts only to hold the sheets together. The staples 43 and 44, however, perform the double function of securing devices for holding the sheets of the signature together and of 110 fastening devices by means of which the signature is held or threaded on the binding devices or yokes of the binder cover. These wire stitches or staples are similar to those used in pamphlet stapling, and may be inserted by the ordinary staple setting machine. The signatures are thus very cheap 115 to assemble and manufacture. The first record section which is supplied with the binder has its first page blank, or may have any 120 suitable title or name. All the other pages of the record section are printed, as shown in Fig. 9, for the entry of deposits and checks drawn. All of the subsequent record sections have their front pages as well as 125 130

the other pages printed for the entry of checks, for a purpose to be hereinafter described.

The check sections or signatures 50 are formed of a plurality of sheets of paper folded on themselves. The folded edges of the check signatures are provided with two sets of notches 51 and 52. The notches 51 and 52 are cut at points on the folded edge 10 of the check signature to coincide with the notches 42 and 41 respectively of a record signature. These notches 51 and 52 are both cut to the same depth. The sheets of the check signature are secured together by 15 wire staples 53, 54 and 55, in a manner exactly similar to the check record sections. The check sheets are perforated or indented at 56 in the usual manner so that the checks may be torn out. The checks on the first 20 half of the pages of the signature are printed to face toward the front of the binder, while the checks printed on the second half of the signature are printed to face toward the back.

25 A number of check signatures are assembled with a single record signature to form a composite record and check signature section. In forming the first composite signature for use in the book, single check signatures 30 are inserted between all of the leaves of the record signatures, the manner of assembling being illustrated in Fig. 11, the notches 51 and 52 coinciding with the notches 42 and 41 respectively. The staples 35 43 and 44 of the record section bridge the ends of the notches 41, and the straight medial portions of the staples thus coincide with the inner edge of the composite signature. The staples 53 and 54 of the check 40 signatures bridge the ends of the notches 51, and the straight medial portions of these staples thus coincide with the inner edges of the check signatures. The notches 42 in the record signatures which coincide with 45 the notches 51 of the check signatures are therefore bridged across somewhat back from their open ends by the plurality of staples 53 and 54 of the check signatures. The binder-arches 10 are inserted through 50 the notches 42 behind the staples 53 and 54, and thus act to hold the check signatures in the record signature so that the compound signature may be supplied as a single composite unit. In securing this composite 55 signature in the binder cover the binder-hooks 6 are first opened, and the composite signature is placed on the binder-hooks by slipping its stapled notches over free ends of the hooks and laid against the front cover. The back cover is then laid over 60 and the two covers are pressed together near the binder-hooks to snap the binder-hooks closed. The signature and the front cover are perfectly held together by the 65 thumb and fingers of the left hand when

the back cover is closed and pressed against the front cover to prevent the staples 43 and 44 from slipping off the binder-hooks. The back cover is then raised, leaving the signatures lying against the front cover. 70 The binder-arches are then secured into their sockets by inserting one of the legs of each arch under one of the lips 24 and snapping the other leg under one of the lips 25, as hereinbefore described. The composite signature is now secured in the binder cover and is ready for use. 75

The check book is now in the condition in which it is intended that it shall be initially given by the bank to the depositor. 80 The number of entry spaces on the second page of the record signature is equal to the number of checks in the first check signature which face this record page. After these forwardly facing checks of the first 85 check signature are used, the record page is balanced and the balance carried to the third page of the record signature. The remaining unused checks in the check signature face backwardly or toward the third 90 page. After the remaining half of the checks in the first check signature have been used, the third page is balanced, and the stub of the used check signatures is torn out. Then the check signature which lies 95 between the fourth and fifth pages of the record signature is used and the record of the checks drawn is entered on the fourth and fifth pages of the record signature, and so on, until all the check signatures in the 100 composite check record and check signature are used. When the last check signature in the composite signature has been used, all of the entry sheets of the record signature will have been used except the very last 105 page. A second composite unit of record and check signatures is supplied by the bank to be inserted in the cover. This second composite signature resembles the first, except that the first page of the record section is printed to record deposits and checks drawn, and that a separate or extra check signature is placed on the front of the second composite section, as illustrated in Fig. 1. As is supplied by the bank this 110 composite signature carries its own wire binder-arches 10. These binder-arches may be turned so that their legs lie back over the outside of the composite signature, and thus act to hold the section together in assembled 115 arrangement. To insert the second composite signature, the previously used record sheets are laid against the front cover, and the binder-hooks 6 snapped open, as hereinbefore described. The binder-arches 10 of 120 the previously used composite filler are then slipped endwise out of their sockets. The record sheets are, however, retained in the binder cover on the binder hooks 6, and laid against the front cover of the binder. 125 130

The composite check record and check section can now be inserted in the manner similar to that in which the first section was inserted. The extra check signature placed on the front of this second composite signature faces the unused last page of the previous record signature upon which the first half of the checks in the extra check signature are to be recorded. The second 10 half of the checks of this extra check signature are to be recorded upon the front page of the second record signature. This insures that all of the pages of the check record signatures are used. After the extra 15 check signature is used the first page of the second record signature is turned over and the checks entered in a manner similar to which the checks were entered in the first signature.

20 Subsequent composite signatures like the second signature are supplied by the bank to be inserted as needed, and so on. The used record signatures are to be kept in the cover as long as they are needed for reference. After a number of used record signatures have accumulated in the book they may be taken out and filed away.

The binder-arches and binder-hooks act to separately hold the two sets of signatures, 30 namely, the check signatures and the record signatures. The binder-arches thus act as a temporary binding means for the check signatures while the binder hooks act as a permanent binding means for the record signatures. It may be noted that since the check signatures lie between the leaves of the record signature, the check signatures will act as an additional means to hold their inclosing record signature in the cover.

40 However often after the composite signature is used and the check signatures have been removed therefrom, the used record signature will be held only by the binder-hooks.

After the bank has supplied a depositor 45 with a cover and an initial signature of record and check sections, the only additional expense is that of supplying the subsequent composite signatures. This is an obvious saving on the part of the bank over the usual 50 method of supplying each time a new cover with permanently bound checks to the depositor. Moreover, the present check book is much more convenient for the use of the depositor, since it allows him to keep a record of former checks in the same book from 55 which he is using checks.

The binder-hooks 6 and binder-arches 10 are located along the binder plate 4 in longitudinal alinement, and they all have a lateral span substantially equal to the width of the binder plate 4. The binder-hooks 6 will, therefore, secure the check record signatures, and the binder-arches 10 will secure the check signatures irrespective of the sequence

or order in which the signatures may be arranged in the binder.

While the form of the invention illustrated in the drawings and described in the foregoing description constitutes the preferred form of the invention because of its 70 simplicity, it is to be understood that the invention may be embodied in other forms within the scope of the following claims:

1. A loose leaf check book, having, in combination, a cover, a binder-plate in the cover, 75 two sets of binder-yokes mounted in said binder-plate, a check signature, and a record signature, each comprising sheets of paper folded upon themselves and having notches cut in their folded edges to fit over both sets 80 of binder-yokes, the check signature being provided with wire staples extending over the ends of the notches engaged by one set of binder-yokes and the record signature being provided with wire staples extending 85 over the ends of the notches engaged by the other set of binder-yokes, substantially as described.

2. A loose leaf check book, having, in combination, a cover, a binder-plate in the cover, 90 two sets of binder-yokes mounted in the binder-plate, a record signature comprising a plurality of sheets of paper folded upon themselves, a plurality of check signatures placed between the pages of the record signature, each check signature comprising a plurality of sheets of paper folded upon themselves, said record and check signatures forming a composite record-signature having a plurality of notches cut in its folded 95 edge, and wire staples for each signature extending over the open ends of certain of the notches in said signature and clenched through the sheets of paper to permanently 100 secure them together, the staples of the record signature extending over the notches engaging one set of binder-yokes and the staples of the check signature extending over the notches engaged by the other set of binder-yokes, substantially as described.

3. A loose leaf book, having, in combination, a cover, a plurality of sets of filler units, and a corresponding number of sets of binding devices located on the cover in longitudinal alinement and in proximity to 115 each other for holding the filler units in substantially the same longitudinal position in the cover, each set of binding devices being adapted to engage and removably secure one of the sets of the filler units, whereby each set of filler units is separately secured in the cover, substantially as described.

4. A composite record and check signature for a loose leaf check book, having, in combination, a record signature comprising a plurality of sheets of paper folded upon themselves, check signatures comprising a plurality of sheets of paper folded upon

- themselves placed between the leaves of the record signature, all of said signatures having a plurality of coinciding binder-receiving notches cut in their folded edges, fastening devices on the record signature over the open ends of certain of the notches, and fastening devices on the check signature over the open ends of certain other of the notches, substantially as described.
- 5 5. A composite signature for a loose leaf book comprising a sheet of paper folded upon itself and having binder-receiving notches cut in its folded edge, fastening devices over the open ends of certain of said notches, a second sheet of paper folded upon itself and having binder-receiving notches cut in its folded edge coinciding with the notches of the first sheet, and fastening devices over the open ends of certain of said notches not coinciding with the notches closed by the fastening devices of the first sheet, said second sheet being placed between the leaves of the first sheet, substantially as described.
- 10 6. A binder for a loose unit book, having, in combination, a cover, a back plate in the cover, a spring binder-arch comprising two substantially parallel legs and a connecting arch portion, said back plate having over turned lips at its sides to form a socket with oppositely opening recesses under the lips to receive the legs of the binder-arch, one of said lips having its free edge extending in a direction inclined to the axis of the back plate whereby the corresponding leg may be snapped into the socket from one side, substantially as described.
- 15 7. A binder for loose units, having, in combination, a cover, a binder-plate in the cover, and means for removably securing the units within the cover comprising two binder-arches adapted to removably receive the loose units, each having a curved head and a pair of legs of spring material extending at an angle therefrom, said binder-plate having a pair of sockets having provision for the reception of legs of the binder-arches therein only when the legs are directed in opposite directions, substantially as described.
- 20 8. A loose leaf book having, in combination, a binder comprising two covers and a connecting back portion, a plurality of sets of filler units, and a corresponding number of sets of fastening devices located in proximity to the connecting back portion of the binder, each set of fastening devices having provision for securing the units of a particular set of filler units in the binder irrespec-
- 25 tive of the sequence in which they are arranged relatively to the units of the other set or sets, substantially as described.
9. A binder for a loose unit book having, in combination, a cover, a binder plate in the cover, and means for securing the units within the cover comprising two binder-arches adapted to receive the loose units each having an arched head and a pair of legs of spring material extending at an angle therefrom, said binder plate having a pair of sockets having provision for the reception of the legs of the binder-arches therein only when the legs are directed in opposite directions and arranged for the insertion of the legs sidewise into the sockets and the removal of the legs endwise from the sockets, substantially as described.
- 30 10. A loose leaf book having, in combination, a cover, a filler unit, and means for securing the filler unit in the cover comprising two binder-arches supplied with and connected to the filler unit, each binder-arch having an arched head and a pair of legs of spring material extending at an angle therefrom, and a binder plate in the cover having a pair of sockets arranged to permit the binder-arches to be inserted sidewise therein with their legs extending in opposite directions when they are connected with the filler unit and to be removed endwise therefrom after the filler unit has been torn from them, substantially as described.
- 35 11. A loose leaf check book having, in combination, a cover, a binder plate in the cover, a check signature, a record signature, a set of binder-yokes mounted in the binder plate for securing the record signature, and a second set of binder-yokes supplied with and connected to the check signature, said binder plate having sockets adapted to receive the second set of binder-yokes when the check signature is inserted and from which the binder-yokes may be removed after the check signature is torn out, substantially as described.
- 40 12. A loose leaf book having, in combination, a binder comprising two covers and a connecting back portion, a binder plate in the connecting back portion, a plurality of sets of filler units, and a corresponding number of sets of wire binder-yokes located along the binder plate in longitudinal alignment and having substantially the same lateral span for separately securing each set of filler units in the binder, substantially as described.
